GAME SCOREKEEPING BOARD

Abigail Van Buren, St. Paul, Minn., assignor to Ideal
Toy Corporation, Hollis, N.Y.

Filed May 12, 1972, Ser. No. 252,732

Term of patent 14 years

Int. Cl. D21—01
U.S. Cl. D34—5 TT

FIG. 1

FIG. 2

FIG. 3

FIG. 4

FIG. 1 of the drawing is a top plan view of a game scorekeeping board embodying my new design.

FIG. 2 is an end view of said device.

FIG. 3 is a perspective view of said device.

And FIG. 4 is a bottom plan view of said device.

I claim:

The ornamental design for a game scorekeeping board, substantially as shown and described.
